ARCH SUPPORT FOR SHOES.

Application filed April 6, 1927. Serial No. 181,539.

This invention relates to arch supports of the kind which are commonly placed into or built into the soles of shoes for supporting the arches of the feet.

- 5 The objects of this invention are to provide an arch support of this kind which will support the arch of the foot at a definite elevation and which at the same time is flexible so as to conform itself to a certain extent to the pressure of the arch on the support; also to form an arch support consisting of two relatively thin flexible members which are so arranged relatively to each other as to form a truss-like structure for supporting 15 the weight of the arch of the foot; also to provide an arch support in which the support is built up of two members which are removable from each other, but which are so locked together that accidental removal 20 of one member from the other or displacement of the members relatively to each other is impossible; also to provide an arch support which can be secured to the inner sole of the shoe and held in place thereby, thus 25 making it possible to construct all other portions of the shoe in the usual manner without varying from the present shop practice except for the preparation of the inner sole before assembling the same into the shoe; 30 also to provide an arch support of this kind which is so constructed that the same interlocks with a rivet or fastening device to entirely prevent accidental disconnection of the arch support with the rivet or other connection; also to provide an arch support 35 of this kind in which a cushion or pad covering the arch support is secured and held in place by a removable member of the arch support; also to provide an arch support of this kind which is particularly well adapted to cooperate with a cushion or pad for cushioning the foot; also to provide an arch support of this kind in which the height of the arch can readily be 40 varied by the use of removable members of different lengths, without removing the other member of the arch support from the shoe; also to provide an arch support which is resilient so that it tends to give the wearer a spring support at the arch of his foot which adds greatly to the comfort of the wearer when walking; also to provide an arch support which is so constructed as to automatically adjust itself to any height of heel; also 45 to improve the construction of arch supports 50

of this kind in other respects hereinafter specified.

In the accompanying drawings,

Fig. 1 is a top plan view of an arch support embodying my invention, showing the 60 same removed from a shoe.

Fig. 2 is a side elevation thereof.

Fig. 3 is a top plan view of the lower or bottom member of the arch support.

Fig. 4 is a central sectional view thereof. 65

Fig. 5 is a top plan view of the upper member of the arch support.

Figs. 6 and 7 are side elevations on a reduced scale showing the manner in which the arch support becomes flexed or bent when 70 pressures are applied at different portions thereof.

Fig. 8 is a central sectional view showing an inner sole of a shoe having my improved arch support applied thereto, and a cushion 75 or padding placed over the arch support.

Fig. 9 is a transverse sectional view thereof on line 9—9 Fig. 8.

Fig. 10 is a fragmentary top plan view of the inner sole, arch support and pad, and 80 showing the cushion or padding turned back to expose the inner sole and arch support.

Figs. 11 and 12 are fragmentary, top plan views illustrating the construction for securing the arch support to the inner sole of the 85 shoe.

Fig. 13 is a fragmentary, sectional elevation thereof on line 13—13, Fig. 11.

My improved arch support includes two members which are secured together so that 90 the intermediate portion of one member, which is made of flexible material, is bowed away from or arched above the other member and places the other member under tension. Preferably both members are made 95 of resilient sheet material of considerable rigidity, such, for example, as spring metal, the lower member A being adapted to be secured to a part of a shoe and flexing or bending therewith during the movement of 100 the foot in the shoe, and the upper member B is secured to the member A. In the particular construction shown, the ends of the upper member are secured to or anchored on the lower member, and this connection between the two members is preferably a detachable one. The lower member is preferably formed or shaped so as to approximately fit the contour of the arch portion of a shoe of normal construction, while the upper 105 110

member B is so formed as to constitute the arch support. In the construction shown the lower member A is provided with a heel portion 15 provided with apertures 16 for securing the heel portion by means of nails or other securing devices to the heel of the shoe. It will be understood, however, that the heel portion of the lower member A may be entirely omitted, if desired, since the operation of my improved arch support is not dependent upon the heel portion thereof. The heel portion preferably has its upper surface dished or concaved as is clearly shown in Figs. 2 and 4 so as to adapt itself 15 to the natural curvature of the heel of a foot.

The upper and lower members may be secured together in their correct relations to each other in any suitable or desired manner but preferably a quickly and easily detachable connection is employed. In the construction shown for this purpose the lower member A is provided, adjacent to the heel of the shoe, with a slot 18 extending crosswise of the foot and another crosswise slot 19 is provided near the other end of the lower member A of the arch support, this slot 19 also having an intersecting longitudinal slot 20 extending rearwardly 25 therefrom, the object of which will be hereinafter explained. The upper or arched member B of the arch support is provided at its front and rear ends with tabs or projections 21 and 22 which are adapted to 30 extend through the slots 18 and 19 respectively, and these tabs or extensions terminate in shoulders 23 and 24. Since the upper member B is made of flexible resilient material, such, for example, as spring 35 brass, this member can be readily bent. Consequently either one of the tabs 21 or 22 is inserted through its slot, and the upper member B is then bent so as to make it 40 possible to insert the other tab or projection 45 through its slot. In order to facilitate the insertion of the tabs of the upper member into the slots 18 and 19, the edges 25 and 26 of these slots are preferably bent or pressed 50 upwardly relatively to the upper face of the lower member A. When the parts are so assembled as shown in Figs. 1, 2, 6, 7 and 8, the tendency of the upper member B to straighten itself out will be resisted 55 by the engagement of the shoulders 23 and 24 at the edges of the slots 18 and 19. The length of the upper member B between the shoulders 23 and 24 thereof is slightly 60 greater than the distance between the slots 18 and 19 so that the upper member must assume an arched or curved shape of a smaller radius of curvature than the curvature of the corresponding part of the lower member A and it will be obvious that the height to which the member B extends 65 above the lower member A depends upon

the length of the member B between the shoulders 23 and 24 thereof.

Since the upper and lower members of the arch support are made of resilient material, such, for example, as spring metal, it 70 will be obvious that the arch support will yield to pressures applied thereto and thus adapt itself to a certain extent to the shape of the foot of the wearer. For example if the pressure is supplied to the arch support mainly in the direction indicated by the arrow X in Fig. 6, the upper member of the arch support will be flexed from the position shown in Fig. 2 to that shown in Fig. 6, 75 the upper member B being bowed forwardly 80 to form a support for portions of the arch which do not press upon the upper member B with the same pressure as that applied at the point X. This results in the application of a more or less uniform pressure to all portions of the arch which is very desirable and which makes this arch support adaptable for arches of different shapes. In Fig. 7 an arrow X' is shown to indicate 85 that the greatest pressure of the arch of the foot is applied at the forward end of the bowed member B. In this case the upper member B is bowed upwardly to a greater extent at the rear portion thereof and thus 90 affords an increased support to portions of the arch exerting less pressure upon the upper member B. Because of this action, my improved arch support readily adapts 95 itself to arches of different shapes and contributes very greatly to the comfort of the wearer since with rigid arch supports trouble is experienced when a portion of the arch 100 presses upon the arch support to a greater extent than other portions of the arch of the foot.

The arch support may be fastened in a shoe in any suitable or desired manner, and also to any desired part of the shoe. It has however been found very desirable to fasten the arch support to the inner sole by the following means:—C represents the inner sole of a shoe, or any other part of the shoe to which the arch support is to be secured, and 110 28 represents a rivet or other attaching device having a head 29 which extends slightly above the upper surface of the inner sole of the shoe. This head 29 is comparatively flat and when the arch support is to be secured to the inner sole, the lower member A is first connected with the rivet head 29 by 115 inserting this head through the slot 19 so that the stem or shank portion of the rivet enters the longitudinal slot 20. This can be readily done as is clearly shown in Figs. 11 and 13. Then upon placing the upper member B into engagement with the lower member, by inserting the tab 21 through the slot 19, the disengagement of the rivet from the lower member A is prevented since the transverse slot 19 is sufficiently obstructed by the 120 125 130

tab 21 of the upper member so that the rivet head 29 cannot pass through the slot 19. Similarly if it is desired to remove the arch support from the inner sole, this can be readily done by first removing the upper member B, so that the rivet head may be passed through the slot 19 out of engagement with the lower member A. When the device is to be permanently secured to a shoe, a nail may be driven through any of the holes 16 in the heel portion of the arch support, or, if desired, a rivet 30, Fig. 8 may be passed through one of the holes 16 and through the inner sole C so that both ends of the arch support are securely held in place on the inner sole. By means of this arrangement described, the arch support need only be connected with the inner sole of the shoe and consequently during the manufacture of the shoe all of the usual steps in the process of manufacturing shoes can be carried out in the same manner as has heretofore been the practice, except in regard to the manufacture of the inner sole which, however, is one of the preliminary steps in the manufacture of shoes. Consequently a shoe of ordinary construction can be very readily converted into a shoe provided with an arch support by merely changing the inner sole, which is an important advantage from the manufacturing standpoint.

Preferably the arch support is covered by means of a pad or cushion, so that the metal of the arch support will not bear directly against the foot. This pad may be in the form of a layer of felt or other padding material D suitably secured to the lower surface of a lining of soft leather or other material E. The construction of my improved arch support lends itself particularly well to the attaching of the cushion D thereto, since a strip of material F which is also preferably of felt or other cushioning material can be passed through the space between the upper and lower members of the arch support and secured at its ends to the sides of the pad or cushion members D and E. Consequently when the pad is to be positioned over the arch support, the upper member B of the arch support is inserted between the positioning strip F and the cushion portion D, and is then attached to the lower member A of the arch support. Consequently the cushion or pad will be held in place by the arch support. In addition the cushion or pad may, of course, be cemented to the upper surface of the arch support and to the inner sole C in the usual manner, if desired. The three parts of the cushion or pad are preferably stitched together at their edges by means of stitches 32. The padding or cushion adds to the comfort of the arch support and by arranging the securing strip F below the upper arch member, this strip does not bear against the foot but helps to

fill the space between the sides of the arch support and the inner sides of the shoe to increase the comfort to the wearer. It will be understood, of course, that the padding or cushion may be omitted or may be replaced by a pad or lining of some other kind. 70

In the use of my improved arch support, the two members thereof are locked together to form a truss-like structure, so that they cannot break down during ordinary wear and thus form a very light but strong arch support. The upper member has sufficient flexibility to conform to different feet and also prevents the lower part from becoming disengaged from the rivet or securing means. Furthermore the arch support is flexible throughout its length and the height of the arch support can be varied by varying the lengths of the upper member. The rivet or part 28 by means of which the arch support is located definitely relatively to the inner sole can be easily positioned uniformly and correctly on the inner soles by the inner sole rounding pattern which has a locating pin 80 positioned in it which punctures the inner sole where the rivet is to be placed. It is also possible to shape the upper member to a certain extent so as to suit the wearer. Since the arch support is flexible, it tends to give a spring to the step rather than to interfere with the free movement of the foot as in ordinary non-flexible arch supports. This feature of my improved arch support allows the arch of the foot a certain amount 100 of exercise and movement which tends to strengthen the same. 95

In considering Fig. 2 it will be obvious that the portion of the lower member A beneath the upper member B is curved so as to follow approximately the curvature of the arch portion of a high heel shoe. However, this same arch support may be used without any changes in a low heel shoe, in which the lower portion A will be flattened to a considerably greater extent than when used in connection with high heel shoes. This is of decided advantage since the flattening out of the lower member A will bring about a corresponding rise or increase in height of 110 the upper member, which is very desirable for the reason that a person requiring arch supports needs a higher arch support when wearing a flat or low heel shoe than when wearing a high heel shoe. 115

I claim as my invention:—

1. An arch support for a shoe including a lower member adapted to be secured to a part of the shoe and having a slot, a fastening device on a part of the shoe adapted to pass through said slot for securing said lower member to said part of the shoe, and an upper member secured to said lower member and bowed upwardly therefrom and having a part adapted to enter said slot to pre- 125

vent said fastening device from moving through said slot to disengage said lower member from said fastening device.

2. The combination of an arch support for a shoe including a lower member having a slot, a fastening device on a part of the shoe including a head portion adapted to pass through said slot into holding engagement with said lower member, and an upper member connected at one end with said lower member and having at its other end a portion adapted to pass through said slot for supporting the intermediate portion of said upper member in a bowed position and extending upwardly above said lower member to support the arch of a foot, said part of said upper member preventing the passage of the head of said fastening device through said slot to release said lower member from 20 said fastening device.

3. The combination of an inner sole for a shoe, a fastening device secured to said inner sole and having a head portion extending upwardly therefrom, an arch support including a flexible member having a slot and a recess connected therewith into which said attaching member may enter after said head has passed through said slot, and an upper arch supporting member adapted to be removably secured to said lower member and having a part extending through said slot for holding said upper member releasably on said lower member and for preventing said attaching device from becoming disconnected from said lower member.

4. An arch support including a lower flexible sheet metal member adapted to be secured in a part of a shoe and having a concave heel portion and a portion extending along the arch of a shoe, and an upper flexible member secured to said lower member in a bowed position so that the intermediate portion thereof extends above said lower member to form a flexible support for 45 the arch of a foot.

5. An arch support including a pair of flexible sheet metal members secured together in such a way that the intermediate portion of one member is bowed relatively to the other member and thereby places said other member under tension, and a cushion sole resting upon said arch support and hav-

ing a portion engaging beneath said one member for anchorage of said sole thereto.

6. An arch support including a pair of flexible sheet metal members secured together in such a way that the intermediate portion of one member is bowed relatively to the other member and thereby places said other member under tension, a cushion sole placed over said arch support, and a part connected to said cushion sole and extending between the members of said arch support for holding said cushion in place thereon.

7. An arch support including a pair of flexible sheet metal members secured together in such a way that the intermediate portion of one member is bowed relatively to the other member and thereby places said other member under tension, a cushion sole placed over said arch support, and a strip of flexible material secured to the edges of said cushion sole and adapted to extend between said upper and lower members of the arch support for releasably holding said cushion sole in place.

8. An arch support for shoes having an inner sole, a flexible plate extending along the same over the arch section thereof, means for securing said plate detachably to said sole, and a flexible arch member attached to said plate adjacent one end of the said arch section extending along and bowed over the arch section and removably attached at its other end to said plate in a manner normally to prevent detachment of said plate from said inner sole while said member is attached to said plate at said other end.

9. An arch support for shoes having an inner sole, a flexible plate extending along the same over the arch section thereof, means for securing said plate detachably to said sole, a flexible arch member attached to said plate adjacent one end of the said arch section, extending along and bowed over the arch section, and removably attached at its other end to said plate in a manner normally to prevent detachment of said plate from said inner sole while said member is attached to said plate at said other end, and a cushion strip disposed over said member and having a section engaged beneath said member to secure said strip thereto.

HENRY J. GLASS.
